(57) **CLAIM**

The ornamental design for a handheld wireless videoconferencing device, substantially as shown and described.

DESCRIPTION

FIG. 1 is a top, front and right side perspective view, in open position, of a handheld wireless videoconferencing device embodying my new design;

FIG. 2 is a front elevation of the device in open position;
 FIG. 3 is a side elevation of the device in open position;
 FIG. 4 is a top plan view of the device in open position;
 FIG. 5 is a rear elevation of the device in open position;
 FIG. 6 is a top, front and right side perspective view of the device in closed position;

FIG. 7 is a plan view of the device in closed position;
 FIG. 8 is an end elevation of one end of the device in closed position;

FIG. 9 is an end elevation of the opposite end of the device in closed position; and,
 FIG. 10 is a side elevation of the device in closed position.
